UNITED STATES PATENT OFFICE.

EDWARD GURNEY, OF TORONTO, ONTARIO, CANADA.

DESIGN FOR A HOT-WATER HEATER.

SPECIFICATION forming part of Design No. 18,547, dated August 21, 1888.

Application filed June 23, 1888. Serial No. 278,049. Term of patent 14 years.

To all whom it may concern:

Be it known that I, EDWARD GURNEY, a subject of the Queen of Great Britain, residing at the city of Toronto, in the county of 5 York, in the Province of Ontario, Canada, have invented and produced a new and original Design for Hot-Water Heaters, of which the following is a specification, reference being had to the accompanying drawing, forming part 10 thereof.

The drawing represents a sectional view of two sections.

The leading feature of my design consists in the rounded upper surface or edge of the inwardly-projecting portion of the section immediately below the fuel-door and the rounded ends of the fire bricks in the said section.

A is the fire brick section. The upper ends,

a, of the bricks, B, and projecting portion of the section A are rounded off. A slanting 20 shelf, C, is placed on top of the bricks immediately in front of the doorway D. The interior surface of the section E, in which is the doorway D, is corrugated.

I claim—

In a design for a hot-water heater, the curved fire-pot section herein described, consisting of the fire-brick section having its upper portion rounded off and a corrugated section above said fire-brick section, substantially as shown.

Toronto, June 13, 1888.

EDWARD GURNEY.

In presence of—

DONALD C. RIDOUT,
CHARLES C. BALDWIN.
